UNITED STATES PATENT OFFICE.

ROBERT L. WELCH, OF CHICAGO, ILLINOIS, ASSIGNOR TO A. G. SPALDING & BROS., A CORPORATION OF NEW JERSEY.

BASE-BALL MASK.

1,196,411.

Specification of Letters Patent. Patented Aug. 29, 1916.

Application filed March 28, 1916. Serial No. 87,347.

To all whom it may concern:

Be it known that I, ROBERT L. WELCH, a citizen of the United States, and a resident of Chicago, Illinois, have invented certain new and useful Improvements in Base-Ball Masks, of which the following is a specification.

My invention relates to base-ball masks and particularly to masks for use of 10 umpires and the invention concerns an improvement in that portion of the mask employed for protecting the ears.

The invention consists in the features of combination and arrangement of parts hereinafter described and pointed out in the claims.

In the accompanying drawings, Figure 1 is a side view of a mask embodying the invention. Fig. 2 is a rear view with the 20 ear pads or protectors folded inwardly. Fig. 3 is a view of the inner side of a protector with a portion of the main part of the mask about which it is pivotally attached.

25 In these drawings 1 indicates generally the main part of the mask composed as usual of a wire frame and an encircling main pad 2.

The ear protectors are indicated generally 30 at 3 and each of these comprises a wire frame made of a substantially semi-circular loop portion 4, the ends of which are provided with eyes 5 encircling the main wire 6 of the main frame and located one above 35 the cross wire 7 and the other below the cross wire 8, so that this wire of the ear protector frame will be allowed pivotal movement but will be retained in position against vertical displacement. The frame 40 of the ear protector further comprises a vertical wire 9 connected at its ends with the semi-circular portion of the frame and also upper and lower bracing wires 10 connected at their ends respectively with the 45 semi-circular wire of the ear protector frame and also the vertical wire thereof.

The ear pad or protector shown at 11 conforms substantially to the shape of the ear being open at the center and having an 50 enlarged lower lobe at 12 and an enlarged portion at its upper part, as shown at 13, the front and back portions of this pad at 14 and 15 being considerably narrower than the upper and lower corner portions, 55 the object being to fully protect the ear but

yet not cover the same in such manner as to interfere with the sense of hearing. This pad is held to the pivoted wire frame by leather flaps 16, 17 secured to the pad in any suitable manner as by stitching, the said 60 flaps being turned over the edge of the frame and lying on the outer sides thereof with their adjacent edges held together by a lacing at 18, this lacing being tied at a suitable point.

65 The mask is held in position on the head in any suitable way but preferably by an overhead strap 19 and a cross strap 20 secured to the overhead strap and attached at its ends by buckles and adjustable straps 21, 70 the latter being connected substantially to the center of the wire frames of the ear pads or protectors. It will be observed that the ear protectors may be folded in so that the mask will not occupy any greater space 75 than that necessary to receive its main portion.

While I have shown the ear pads of a shape to encircle the opening of the ear and while I have shown these pads as separate 80 from the main pad of the mask I do not limit myself in these respects, nor do I limit myself to the particular construction of the parts described. Either ear pad may be readily removed for repair or for replacement.

85 It will be observed that the user of the mask may pack it in a small space in his grip in transporting it from place to place.

80 What I claim is:—

90 1. A base-ball mask comprising a main frame and pad and ear protectors pivotally mounted on said main frame and adapted to be folded in relation to the main frame and pad, said ear protectors comprising 95 frames pivoted to the main frame and having pads individual thereto and independent of the main pad, substantially as described.

99 2. In combination in a base-ball mask 100 a main pad, a frame holding the same and projecting wholly to the front thereof leaving the rear of said pad in substantially one plane and ear protectors mounted pivotally 105 on the main frame and folded into the space within the main pad leaving the rear face of the main pad and the outer faces of the ear protectors substantially in the same plane when said protectors are folded, substantially as described.

110

3. In combination a main pad, a frame carrying said pad, a supplemental frame pivotally mounted on the main frame and comprising a substantially semi-circular member with a vertical bar connecting the upper and lower portions thereof adjacent the pivot, a pad on the inner side of said supplemental frame and flaps connected with said pad and extending around the vertical rod and the semi-circular portion of the supplemental frame with means for securing said flaps together, substantially as described.
4. In combination a main frame, a main pad, an ear protector frame pivotally mounted on the main frame and a pad removably mounted on the said pivoted frame, substantially as described.
5. In combination in a base-ball mask, a main frame with its pad, an ear protector frame pivotally mounted on the main frame, a pad for protecting the ear, said pad having flexible extensions overlying the outer side of the frame with means for securing

said extensions together to hold the pad in place, substantially as described.

6. In combination a main frame with its pad, a substantially semi-circular frame pivotally mounted on the main frame, a pad on the inner side of the semi-circular frame for protecting the ear, flaps connected with said ear pad and overlying the outer side of the pivoted frame with means for securing said flaps together, substantially as described.

7. In combination a main frame with its pad, ear protector frames pivotally mounted on the main frame and each having an ear pad, a head strap and an adjustable cross strap, said cross strap being connected with the pivoted ear protector frames, substantially as described.

In testimony whereof, I affix my signature.

ROBERT L. WELCH.
